(57) **CLAIM**

The ornamental design for a mat, as shown and described.

DESCRIPTION

FIG. 1 is an upper perspective view of a mat showing my new design;

FIG. 2 is front view thereof;

FIG. 3 is a rear view thereof;

FIG. 4 is a side view thereof;

FIG. 5 is an opposite side view thereof;

FIG. 6 is a top plan view thereof; and,

FIG. 7 is an enlarged view of the encircled portion the mat shown in FIG. 1.

The bottom of the mat, which is not illustrated in the drawings, forms no part of the claimed design. The broken lines in FIGS. 1 and 7 represent enlarged areas and do not form part of the claimed design.
